BOTTLE CAP

Martin A. Jaffe, New York, N. Y., assignor to Nutrilite Products, Inc., Buena Park, Calif., a corporation of California

Application May 6, 1957, Serial No. 46,031

Term of patent 14 years

(Cl. D58—26)

Fig. 1.

Fig. 4.

Fig. 2.

Fig. 5.

Fig. 3.

Fig. 6.

Figure 1 is a perspective view of a bottle cap embodying my new design;

Figure 2 is a rear elevation view thereof;

Figure 3 is a front elevation view thereof;

Figure 4 is a sectional view thereof;

Figure 5 is a top plan view thereof; and

Figure 6 is a bottom plan view thereof.

The dominant features of my design reside in the portions shown in full lines.

I claim:

The ornamental design for a bottle cap, as shown and described.
